UNITED STATES PATENT OFFICE.

ELLA GOODWIN, OF CHICAGO, ILLINOIS.

WASHING-MACHINE.

SPECIFICATION forming part of Letters Patent No. 326,903, dated September 22, 1885.

Application filed April 11, 1884. (No model.)

To all whom it may concern:

Be it known that I, ELLA GOODWIN, of Chicago, State of Illinois, have invented certain new and useful Improvements in Washing-Machines, of which the following is a specification.

The invention consists in a washing-machine constructed as hereinafter described and claimed.

10 The accompanying drawings illustrate the invention. Figure 1 is a central vertical section. Fig. 2 is an open top view, the cover being taken off. Fig. 3 is an enlarged vertical section through a portion of the rubbers.

15 A designates a cylindrical vessel or tub, which is preferably made slightly tapering from the top to the bottom in the interior opening. A common wash-tub will answer very well for the cylindrical vessel of a hand-made chine.

In the bottom of the vessel is applied the under stationary rubber, B, which is made highest in the center, from which it gradually slopes to the circumference, the form of the 25 upper surface being that of a low wide-based cone or conoid.

30 The upper rubber, C, is concaved on its under side to correspond with the upper convex surface of the lower one. The rubbers are best made in sections or blocks c in the form of a sector. Their facing surfaces are corrugated, as seen at c' c", Fig. 3, the corrugations in each section running about parallel with one of the radii.

35 The upper rubber is attached to a shaft, D, which passes up through the cover E and loosely through the bore of a pinion, a, which has its hub or sleeve journaled in a bracket, F, which supports a shaft, a', provided with 40 a crank, G, and pinion a'', engaging with pinion a. The shaft D has a long key, a''', secured thereto, which slides in a groove in the bore of the pinion, so that said shaft may rise and fall while remaining subject to the rotary motion of the pinion.

45 The cover E is hinged together at e, the larger part thereof being free and having the bracket F firmly attached thereto, and the smaller part being secured to the tub, so that 50 it will support the other part when turned back or opened as a lid, the crank G being first

taken off. When so opened, the upper rubber will be lifted out of the tub.

A' is a faucet for drawing off the water. The elevated center of the rubbers prevents the 55 clothing while being washed from collecting in a bunch in the center.

The operation is as follows: The crank being taken off, the lid is turned back and the clothes put into the tub with soap and hot water. 60 The lid is then shut down. This brings the upper rubber on top of the clothes, and the play of shaft D up and down adapts the upper rubber to the quantity of clothes between the rubbers, and when resting down 65 upon them of its own weight the upper rubber is rotated or oscillated back and forth by means of the crank until sufficient rubbing is done and the clothes are cleansed, when they are taken out.

70 The principle of the rubbers with the elevated center may be applied both to hand and power machines, and the facility with which the rubbers so made and provided with the hinged cover, bracket, &c., may be adapted 75 and applied to a common wash-tub renders these parts themselves useful and valuable.

75 My invention does not include machines not having the facing-surfaces of the rubbers made highest at the center and gradually sloping 80 therefrom to the circumference, nor machines with the rubbers whose surfaces are formed of radial wedge-shaped ribs or spokes with open space between the spokes, and having a standard or other obstruction extending through the 85 space between the rubbers, even though such rubbers should be highest in the center, for it is necessary that the surfaces of both the rubbers should be continuous, not as open spokes, in order to rub small articles or the edges of 90 larger ones, as the collar and wrist-bands of shirts, sufficiently to cleanse them, and the space between the rubbers at the elevated center should not be obstructed. I do not wish to be understood as claiming any machine having rubbers with flat facing surfaces; nor any machine with a standard or other obstruction extending through the space between the rubbers at the center, or with one or both of the rubbers made of raised spokes with open spaces 95 between them.

100 What I claim is—

In a washing machine, the rubbers B C, having their coincident faces composed of a continuous surface made highest in the center and gradually sloping therefrom to the circumference, such surface being laid off in sectors and provided with corrugations in each sector running parallel with one of its radii, said rubber B being fitted into the bottom of a tub or vessel, as A, and said rubber C being sup-

ported on a shaft, D, terminating in and connected to the upper side of said rubber, and supported in a bracket, as F, attached to the lid and provided with gearing and a crank for operating the same, substantially as specified.

ELLA GOODWIN.
